UNITED STATES PATENT OFFICE

JOHN F. MARTIN, OF CHICAGO, ILLINOIS.

INSULATOR FOR UNDERGROUND ELECTRIC CONDUCTORS.

SPECIFICATION forming part of Letters Patent No. 286,947, dated October 16, 1883.

Application filed March 12, 1883. (No model.)

To all whom it may concern:

Be it known that I, JOHN F. MARTIN, a citizen of the United States, residing in Chicago, county of Cook, and State of Illinois, have invented certain new and useful Improvements 5 in Insulators for Underground Electric Wires, of which the following is a specification.

This invention relates to improvements in means for insulating and supporting the electric conductors of an underground system, and has for its object to provide a durable and efficient construction of insulator which can be readily introduced into or removed from the conduit; to provide for supporting and insulating from each other a large number of wires; to admit of the wires being drawn through the insulator as required or taken out when necessary; and, finally, to prevent induction and all disturbance heretofore incident to such 20 common failings in underground systems.

To such end my invention consists in an insulator constructed as hereinafter fully described, and illustrated in the annexed drawings, in which—

25 Figure 1 represents two sections of a conduit-pipe coupled together and inclosing two of my improved insulators, shown coupled and partly in section. Fig. 2 is an end view of one of the insulators fitted within a conduit-pipe. 30 Fig. 3 shows, partly in section, a portion of one of the insulators.

The insulator consists of a block or section, A, composed of asphaltum or asphaltum cement molded into cylindrical or substantially cylindrical form, with a series of longitudinal bores, B, running from end to end. These bores or perforations are arranged in parallel lines, and constitute continuous individual wire-chambers for the electric wires when the 35 blocks or sections are joined. As it is designed that a separate chamber shall be provided for each individual wire, the number of chambers should, therefore, be equal to the greatest number of wires which will be required. The insulators A are made in the 40 form of cylindrical sections, and as a means for supporting the same within a conduit-pipe, and also for preventing the insulator from turning during or after its introduction into 45 the conduit, I provide each insulator with longitudinal ribs or tongues C, adapted to fit in

grooves formed in ribs D, which run along the inner wall of the pipe.

In Fig. 1 I have shown a pair of my perforated insulators coupled together by means of 55 short tubes, which are fitted at their ends into the perforations in the blocks, so as to render the passages for the wires continuous throughout the line. As more clearly shown in Fig. 4, the diameter of each one of the passages B is 60 enlarged at its end, so as to form a seat, B', for the coupling-tube, which, being fitted in said seat, will thereby connect the passages of adjacent insulators.

In coupling the insulators together the tubes 65 E are fitted in the seats B' in the insulators and a space left between the opposing ends of the latter. This intervening space is then filled with asphaltum or other cement, which process can be effected by temporarily arranging 70

a band or casing over the ends of the insulators and the tubes between the two, so as to hold the cement in place until it has set. In this way a filling, F, of cement can be placed 75 between the ends of the perforated insulating blocks, so as to connect them together, and also embed the coupling-tubes and form airtight joints. In Fig. 3 I have shown each passage provided at its end with two seats, the outer one of which is somewhat larger in diameter than the inner one. This arrangement 80 is preferably adapted where bends occur in the line and it becomes necessary to provide bent passages for the wires. In this instance the tubes E are fitted in the smaller seats B', 85 and upon these tubes are fitted the flexible coupling-tubes G, which latter are also received in the seats B' at the ends of the passages through one of the insulators. By thus arranging the coupling-tubes E and G close 90 joints will be formed and the tube G be allowed to be bent according to the direction in which the wires are to be carried. These bends occur at branches along the main, or at drawing-in boxes or distributors, and at all 95 such points couplings, as herein shown, can be provided. The asphaltum employed for forming these perforated insulators can be combined with any suitable material and then 100 molded into the required shape, and after hardening it will be found that wires can be introduced and passed through passages B of

considerable length, and hence that each insulator A can be made quite long, if desired, which will avoid the too frequent occurrence of couplings along the line.

5 Boxes or traps will in practice be connected with the conduit at intervals for the purpose of allowing the wires to be laid, taken out, or inspected.

Having thus described my invention, what I
10 claim, and desire to secure by Letters Patent,
is—

1. The combination, with a conduit-pipe, of
the perforated asphaltum insulator in sec-
tions, joined together so as to form continuous
15 individual wire-chambers, and fitted within

the pipe, and connected therewith by a tongue
and groove, substantially as described.

2. The combination, with a conduit-pipe, of
the perforated asphaltum insulator, made in
sections, joined together so as to form continu- 20
ous individual wire-chambers, the coupling-
tubes having their ends received in seats in
the ends of the chambers in the said sections,
and the cement filling F, disposed as herein
described and for the purposes set forth.

JOHN F. MARTIN.
